UNITED STATES PATENT OFFICE.

FREDERICK A. GALE, OF CHICAGO, ILLINOIS.

AUTOMATIC BLOWER FOR LOCOMOTIVES.

Application filed March 23, 1921. Serial No. 454,802.

To all whom it may concern:

Be it known that I, FREDERICK A. GALE, a citizen of the United States, residing at Chicago, in the county of Cook and State of Illinois, have invented certain new and useful Improvements in Automatic Blowers for Locomotives, of which the following is a specification.

This invention relates to means for disposing of smoke and gases of combustion of locomotives at times when steam is shut off from the cylinders and normal discharge of steam upward through the stack is absent. In a locomotive, and especially with a green fire or fire from which the more volatile constituents of the freshly added coal have not had time to distill, shutting off of the steam from the cylinders and consequent interruption of exhaust upward through the stack leaves the smoke and gases of the fire, particularly in heavy weather, free to settle down around the locomotive and over adjacent tracks, and causes great danger of accident by obscuring signals from the vision of the engineer, and the moving cars on adjacent tracks from the vision of operatives who may be working on and about the same. Moreover, such smoke and gases frequently become a source of great annoyance and inconvenience to passengers in adjacent cars.

The present invention has for its object to provide means for automatically opening a steam connection from the boiler to develop forced draft upward through the stack when the throttle of the engine is closed, and to shut off such supply of steam from the boiler whenever the throttle is open.

A further object is to utilize the automatic control of such steam to govern the supply of steam to the fire.

Still another object is to provide means for bringing either of the steam supplies, that delivering to the stack and that delivering to the fire, under said automatic control, at will, and to regulate the extent to which each becomes responsive to the automatic control.

The invention proceeds upon the principle of taking live steam from the boiler and delivering it in suitable position to serve the function stated; that is to say, delivering it beneath the petticoat pipe to take the place of exhaust steam for blowing the fire, and delivering it through jet nozzles at the sides of the fire for consuming the smoke, and

providing an automatic valve for the control of these deliveries which is opened and closed reciprocally with the opening and closing of the engine throttle; suitable hand controlled valves being introduced beyond the automatic valve, in the branch pipes which lead to the blower and fire jets; and the valve which automatically controls the live steam delivery being preferably in the nature of a piston valve which will close under pressure of steam released by the throttle, but will automatically open when relieved of such pressure.

In the accompanying drawing.

Figure 1 is a diagrammatic view of a locomotive to which the preferred embodiment of the subject-matter of the present invention is applied.

Figure 2 is a side elevation of the automatic valve employed in the arrangement of Figure 1; and

Figure 3 is an axial section of the valve shown in Figure 2.

A represents the throttle valve of an engine, and A' the controlling mechanism for such valve, which usually extends within reach of the engineer and is adapted to be manipulated to unseat the valve and admit steam to the dry-pipe leading to the steam chest A². B represents the petticoat pipe located in the smoke box beneath the stack. C is the exhaust nozzle which usually delivers beneath the petticoat B for the purpose of inducing a partial vacuum in the smoke box at the front end of the tubes and thereby causing a forced draft through the fire and tubes. D represents an annulus surrounding the exhaust nozzle C or any other suitable attachment through which live steam may be delivered in the same relation to the petticoat B as that in which steam is delivered from the exhaust nozzle C. The attachment D is merely typical of some suitable means for delivering live steam in the relation stated. E represents a supply pipe for the attachment D, which leads from some suitable source of live steam, for instance, from the upstanding end E' in the steam dome F. G represents a valve adapted to be manipulated by hand for the purpose of controlling the flow of steam through the pipe E to the attachment D.

M represents a branch pipe taking steam from the pipe E in volume regulated at will by the hand valve M' and supplying it to the steam jets M², of known construction, which

- deliver steam to the fire as an additional combustion-supporting medium or smoke-consuming expedient. To regulate the steam flowing through pipe E, said pipe is 5 provided with a hand controlled valve E². By regulating the valves E² and M', the distribution of the steam to the attachment D and the jets M² may be proportioned at will.
- 10 As thus far described, the organization of parts is capable of manipulation to deliver live steam in draft-inducing relation to the smoke box at will, so that forced draft may be maintained whenever the locomotive is 15 at rest and draft-inducing steam is not being supplied by the exhaust nozzle. But it is desirable to render the opening and closing of the pipe E automatically reciprocal with the opening and closing of the locomotive 20 throttle A. To this end, a specially constructed valve H is introduced at some suitable point in the pipe E for the purpose of controlling the flow of live steam through the pipe, and this valve H has its rod H' 25 equipped with a piston H² working in the cylinder H³, to one side of which steam released by the throttle A is communicated, as for instance through the pipe K leading from the dry pipe A² between the throttle A 30 and the steam chest A³, while the other side of said piston H² is subjected to a counter-pressure, for instance, the pressure of live steam standing in the advance portion of pipe E, with the result that whenever the 35 throttle A is open and a working pressure of steam is admitted to the dry-pipe A², a portion of said steam will flow through pipe K to the piston H² and force the latter downward to seat the valve H. But whenever the 40 throttle A is closed, and pressure above the piston H² is relieved, the pressure of live steam beneath the piston H² lifts the valve H from its seat and permits steam to flow from the advance portion of pipe E to the 45 discharge end thereof, and serve the blowing attachment D beneath the stack.
- Suitable means are provided for differentiating the effect of steam pressure upon opposite sides of piston H². In the embodiment of the invention selected herein for purposes of illustration, this consists of a coil spring H⁴ located on the side of the piston to assist the throttle-controlled pressure medium in seating the valve. When 50 the valve is seated the force opposing the throttle-controlled pressure of pipe K and the spring H⁴ is reduced by the superficial area of the head of the valve H so long as the latter is upon its seat.
- 55 60 In order to control the admission of steam to the valve H², a valve L may be introduced into the pipe K. Obviously, if the valve L

should be closed, it will be possible to use the same arrangement to maintain live steam blowing simultaneously with the exhaust 65 steam blowing, in case it should be desirable to augment the draft on the fire while the engine is proceeding very slowly and the volume of exhaust is correspondingly small.

By the use of the valve G the auxiliary 70 blowing equipment may be kept entirely out of action when not needed, as, for instance, when the locomotive is making infrequent stops and the draft is ample during running periods to maintain the fire without the consumption of live steam. Similarly, by opening valve G and closing valve E² the jets M² 75 will be automatically supplied to the exclusion of the blowing device D, and by leaving valve E² open and closing valve M', the blowing device may be used to the exclusion 80 of the steam jets.

I claim:

1. In a forced draft attachment for locomotives, means for delivering steam in draft 85 inducing relation to the fire of the locomotive, a pipe for supplying said steam, a throttle having connections for supplying steam to the locomotive, and a steam actuated valve in said pipe receiving steam released 90 by the throttle; said valve having a cylinder which is subjected on one side to the pressure of steam which it controls, and on the other side to the pressure of steam released by the throttle; and means independent of the 95 throttle released steam being provided on said side subjected to steam from the throttle for augmenting the pressure of the latter.

2. In a forced draft attachment for locomotives, means for delivering steam in draft 100 inducing relation to the fire of the locomotive, a pipe for supplying said steam, a throttle having connections for supplying steam to the locomotive, and a steam actuated valve in said pipe receiving steam released 105 by the throttle; said valve having a cylinder which is subjected on one side to the pressure of steam which it controls, and on the other side to the pressure of steam released by the throttle, and a spring being provided on said side subjected to steam from the throttle for augmenting the pressure 110 of the latter.

3. In combination with a locomotive, a blower, a jet adapted to supply steam to the fire, and automatic means controlled by the supply and shutting off of locomotive propelling steam governing the supply of steam to said blower and jet; said blower and jet having independent means for governing the proportion of such steam that reaches them. 115

Signed at Chicago, Illinois, this 18th day of March, 1921.

FREDERICK A. GALE.
